UNITED STATES PATENT OFFICE.

ELEAZAR CATE, OF BELMONT, MASSACHUSETTS, ASSIGNOR TO L. E. KNOTT APPARATUS COMPANY, OF BOSTON, MASSACHUSETTS, A CORPORATION OF MASSACHUSETTS.

DESIGN FOR A BASE FOR PHYSICAL-LABORATORY APPARATUS.

44,334.

Specification for Design.

Patented July 15, 1913.

Application filed March 22, 1912. Serial No. 685,576. Term of patent 14 years.

To all whom it may concern:

Be it known that I, ELEAZAR CATE, a citizen of the United States, residing at Belmont, county of Middlesex, State of Massachusetts, have invented a new, original, and ornamental Design for a Base for Physical-Laboratory Apparatus, of which the following is a specification, reference being had to the accompanying drawing, forming part thereof.

The figure is a perspective view of a base for physical laboratory apparatus showing my improved design.

I claim:

The ornamental design for a base for physical laboratory apparatus as shown.

In testimony whereof I have signed my name to this specification in the presence of two subscribing witnesses.

ELEAZAR CATE.

Witnesses:
